UNITED STATES PATENT OFFICE.

WILLIAM KREANNER, OF RIPLEY, OHIO.

APPARATUS FOR DELIVERING AND RECEIVING MAIL.

No. 923,977.

Specification of Letters Patent. Patented June 8, 1909.

Application filed March 10, 1909. Serial No. 482,436.

To all whom it may concern:

Be it known that I, WILLIAM KREANNER, a citizen of the United States, residing at Ripley, in the county of Brown and State of Ohio, have invented a new and useful Apparatus for Delivering and Receiving Mail, of which the following is a specification.

This invention relates to apparatus for delivering and receiving mail, the same being of that type used for effecting an interchange of mail between moving mail cars and stations along the route traveled by the cars.

The object of the invention is to provide a crane of novel form for supporting a mail bag in such a manner as to permit its ready delivery, said crane also having means for engaging a bag-supporting ring without danger of the bag becoming accidentally dis- placed and dropping to the ground.

A further object is to provide a crane of this type designed to be mounted upon a mail car and to swing automatically into the car subsequent to the interchange of mail and to be automatically swung outwardly beyond the wall of car before the interchange of mail is effected.

A further object is to provide novel means for locking the crane in either of its two positions, said lock being under the control of a tripping device located close to the track and separate from the car.

Another object is to utilize fluid under pressure for the purpose of actuating the crane, said fluid being preferably compressed air such as used in air-brake systems.

With these and other objects in view the invention consists in certain novel details of construction and combinations of parts hereinafter more fully described and pointed out in the claims.

In the accompanying drawings the preferred form of the invention has been shown.

In said drawings:—Figure 1 is a perspective view of the complete apparatus constituting the present invention, the various parts being shown in the relative positions assumed by them immediately prior to the interchange of mail. Fig. 2 is a side elevation of a portion of a car and the mechanism thereon, the crane lock being shown in section and the crane being extended outwardly beyond the car wall. Fig. 3 is a

vertical transverse section through a portion of a car and showing the mechanism partly in elevation and partly in section, one of the positions of the crane being indicated by dotted lines. Fig. 4 is an enlarged section on line A—B Fig. 3. Fig. 5 is an elevation of the crane locking bolt, the guide plate and the movable disk being shown in section. Fig. 6 is a side elevation of the pitman actuated wheel and the eccentric adjacent thereto. Fig. 7 is a view partly in side elevation and partly in section of a portion of one of the bag receiving devices.

Referring to the figures by characters of reference A designates a platform at a station and extending upwardly therefrom is a standard 1 to the upper portion of which is adjustably secured a ring 2 having an arm 3 outstanding therefrom. This arm is provided at its outer end with an inverted U-shaped member 4 to the ends of which are secured parallel arms 5, said arms extending from both ends of the member and one of the arms being provided at its ends with outwardly retaining springs 6 designed to prevent accidental displacement of a bag-supporting ring 7 after said ring has been placed upon the arms. Secured to the lower portion of the standard 1 is another ring 8 having an arm 9 extending therefrom, said arm being provided with an upturned end portion 10 having a bowed bag-engaging member 11 secured to the lower portion thereof, while mounted on the upper portion of the upturned end 10 is another bag-engaging member 12. This last mentioned member has dogs 13 pivotally connected to its ends and the free ends of the dogs are designed to rest normally upon the member 11. Said member 11 is so shaped as to prevent the dogs from moving in one direction to such an extent as to permit the escape of a bag from between the members 11 and 12 after the bag has been placed in position therebetween.

The car structure B has a standard 14 mounted for rotation within the door opening b and extending from the upper portion of this standard 14 is an arm 15 similar to the arm 9 and provided with an upturned outer end portion 16 on which are mounted upper and lower bag-engaging members 17 and 18 respectively, the lower member 18

being bowed and constituting an abutment for dogs 19 which are pivotally connected to the end portions of the member 17. Another arm 20 extends outwardly from the 5 lower portion of the standard 14 and is provided at its outer end with an inverted yoke 21 to the lower ends of which are secured parallel oppositely extending arms 22, one arm being provided at each end with an out- 10 turned retaining spring 23. By referring to the drawings it will be seen that this arm 20 and the parts connected thereto are similar in all respects to the arm 3 and the parts thereon. The bag-engaging members 17 and 15 18 are so disposed when extended beyond the car structure B, as to travel between the arms 5 on the stationary bag-delivering member, and the arms 22 are so arranged when the crane is extended beyond the car struc- 20 ture, as to receive between them the bag-engaging members 12 and 11 carried by the standard 1.

The standard 14 extends through the floor of the car body B and that portion thereof 25 below the car floor is provided with upper and lower spaced mutilated pin tooth gears 24 and 25 respectively, the pins upon the said gears being designed to be alternately engaged by the pins on a mutilated pin tooth gear 26 which is arranged at one end of a shaft 27 journaled within hangers extending downwardly from the bottom of the car structure. This shaft 27 has a wheel 28 at one end provided with a wrist-pin 29 on 30 which is mounted a pitman 30 designed to transmit motion to the wheel and shaft from the rod 31 of a piston mounted to reciprocate within a cylinder 32 disposed upon the bottom of the car. This cylinder is provided 35 with an ordinary slide valve (not shown) the rod 33 of the valve being actuated by an eccentric 34 which rotates with the shaft 27. A pipe 35 opens into the valve casing 36 and is designed to convey fluid under pressure to 40 the casing from any suitable source.

A disk 37 rotates with the standard 14 and is located below the car bottom, said disk being provided at diametrically opposed points with apertures 38 and 39, 45 either one of which is designed to receive a locking bolt such as illustrated in detail in Fig. 5. This bolt consists of a stem 40 slidably mounted within a guide plate 41 and provided at one end with a U-shaped exten- 50 sion 42, the free end of which is designed to project into one of the openings 38 and 39 and thus hold the disk 37 against movement. A spring 43 is mounted upon the stem 40 and bears upwardly against the plate 41 and 55 downwardly upon a pin 44 extending through the stem 40, this spring thus serving to hold the upper end of the bolt normally in engagement with the disk. The lower end of the stem 40 carries a roller 45 which is held

by the spring 43 normally pressed downwardly a sufficient distance to strike and ride upwardly upon a curved tripping plate 46 arranged close to one of the rails of the track. A supporting bracket 47 may be secured to the car body so as to constitute a 65 70 75 guide for the stem 40 as indicated especially in Figs. 1 and 2.

It is to be understood that when the crane upon the car is in its normal position the arms 15 and 20 extend inwardly into the car structure as indicated by dotted lines in Fig. 3. While the parts are thus located a ring such as indicated at 48 may be placed around the arms 22 and a bag suspended therefrom as shown in Fig. 1. The spring 80 85 80 upon one of the arms will act to prevent accidental displacement of the ring 48.

When the car approaches a station where the mail is to be delivered the roller 45 moves against and rides over the tripping plate 46 located at the near side of the stationary crane mounted adjacent the track. As soon as the roller 45 moves upwardly on the tripping plate 46 the upper or locking end 42 of the stem 40 is lifted out of the opening 39 in which it is seated and as the valve in casing 36 is opened the fluid under pressure will rush into the cylinder 32 and drive the piston 90 therein in one direction so as to produce a one quarter rotation of the shaft 27 after which 95 the eccentric 34 will shift the valve within casing 36 so as to cause the piston within cylinder 32 to move in the opposite direction and produce an additional one quarter turn of the shaft 27. As soon as the 100 one half rotation of the shaft produced by these two strokes of the piston has been completed the spring-controlled stem 40 will be forced downwardly so as to bring its end 42 into the other opening 38 within the 105 disk. Further operation of the piston and the shaft 27 is thus prevented. It is of course to be understood that the disk receives its motion from the shaft 27 through the pin tooth gears 24 and 25, and when the standard 110 14 and the disk 37 have completed their one half revolution so as to bring the arms 15 and 20 beyond the wall of the car structure B, the pins upon the upper gear 24 are brought into position to be engaged by the 115 pins on the gear 26 during the next half rotation of said gear.

As heretofore stated the foregoing operation swings the standard 14 so as to bring the arms 15 and 20 beyond the car structure 120 as shown in Figs. 1 and 3. As the car passes the stationary crane the arms 22 move along opposite sides of the bag-receiving members 11 and 12 and the ring carried by the arms 22 move between said members and pushes the adjoining dog 13 upwardly. This dog promptly falls back to its normal position and accidental removal of the ring from be-

tween members 11 and 12 is thus positively prevented. Should a ring 7 be suspended from the arms 5, the members 17 and 18 will pass between the arm 5 while the fore-
5 going operation is taking place, and said ring 7 will thus pass between the members 17 and 18 so that the bag carried by it will be transferred to the member 18. After the car passes the stationary crane the roller 45
10 passes over a second tripping plate 48 and the disk 37 is thus a second time released and the fluid under pressure within the cylinder 32 therefore operates to impart a one-half revolution to the shaft 27 and the gear 26
15 therefore engages the gear 24 and imparts a one-half rotation to the standard 14, this resulting in the arms 15 and 20 swinging back into the bar structure B and carrying with them the bag that has been delivered
20 thereto.

It will be seen that this mechanism is automatic in all of its operations, the only attention required being that of placing a bag upon the arms 22 and removing the collected
25 bag from between the members 17 and 18. As soon as the interchange of mail has been effected those parts of the apparatus projecting beyond the car swing automatically back into the car, and they remain there
30 until just prior to the arrival of the car opposite a point where the interchange of mail is to occur. There is therefore no danger of these projecting parts coming into contact with passing trains and the like.

35 Obviously various changes may be made in the construction and arrangement of the parts without departing from the spirit or sacrificing the advantages of the invention. For example, a stop-lug 37' may be extended
40 radially from the disk 37 and move against oppositely disposed studs 38' for the purpose of limiting the movement of the crane.

What is claimed is:-

1. The combination with a car structure, 45 of a crane mounted for partial rotation thereon, power mechanism for actuating the crane, means for locking the crane against movement, and means for automatically releasing the crane at a predetermined point
50 during the movement of the car.

2. The combination with a car structure, 55 of a crane mounted for partial rotation thereon, power mechanism upon the car structure for successively swinging the crane beyond the structure and returning it thereto, means for automatically locking the said mechanism immediately subsequent to each of said movements, and means for automatically unlocking the mechanism at predetermined points during the movement of the car.

3. The combination with a car structure, 60 of a crane mounted for partial rotation thereon, and power mechanism carried by

said structure for successively swinging the 65 crane beyond the structure and returning it thereto automatically, and means for controlling the operation of the mechanism.

4. The combination with a car structure, 70 of a crane movably mounted thereon, mechanism for automatically actuating the crane to project it beyond the car structure and to swing it into said structure successively, means for locking the crane against the action of said mechanism, and means for 75 releasing the crane at predetermined points.

5. The combination with a car structure, 80 of a crane movably mounted thereon, means for automatically actuating the crane to project it either beyond the car structure or into said structure, locking members normally coöoperating to hold the crane against the action of said operating means, a relatively fixed tripping member, and means carried by one of the locking members for engaging 85 the tripping member to release the crane.

6. The combination with a car structure, 90 of a crane movably mounted thereon, a revoluble shaft, means actuated by the shaft when rotated in one direction to rock the crane, mechanism for automatically actuating the shaft, coöoperating locking members for holding the shaft and crane against movement, and a tripping device in the path of one of said members for actuating the 95 member to release the crane and shaft.

7. The combination with a car structure, 100 of a crane mounted for partial rotation therein, an apertured member movable with the crane, a spring-controlled locking member normally engaging said movable member to hold the crane against movement, a revoluble shaft, means upon the shaft and crane for transmitting a rocking movement to the crane from the rotating shaft, means 105 for automatically actuating the shaft when released from the locking means, and a tripping device for unlocking the shaft and the crane at a predetermined point during the movement of the car.

8. In mechanism of the class described a 110 mail-receiving member comprising a supporting structure, spaced upper and lower bag-receiving members carried thereby, said lower member having an intermediate bowed portion, and retaining dogs pivotally connected to the ends of the upper member and bearing against the bowed portion of the lower member, said dogs constituting bag-retaining means, the ends of the lower member being extended beyond the corresponding ends of the upper member.

9. In mechanism of the class described a 115 bag-delivering device comprising a supporting structure, an arm outstanding therefrom, 120 an inverted U-shaped member carried by the arm, and parallel arms supported by the U-shaped member.

10. In apparatus of the class described
bag-delivering mechanism comprising a sup-
porting structure, an inverted U-shaped
member carried thereby, parallel arms sup-
ported by the U-shaped member, and retain-
ing springs outstanding from one of the
arms.

In testimony that I claim the foregoing
as my own, I have hereto affixed my signa-
ture in the presence of two witnesses.

WILLIAM KREANNER.
